UNITED STATES PATENT OFFICE

149,702

DESIGN FOR AN AUTOMOBILE TRAILER

Walter C. Smith, Buffalo, N. Y.

Application March 8, 1946, Serial No. 127,260

Term of patent 7 years

(Cl. D14—3)

To all whom it may concern:

Be it known that I, Walter C. Smith, a citizen of the United States, residing at Buffalo, in the county of Erie and State of New York, have invented a new, original, and ornamental Design for an Automobile Trailer, of which the following is a specification, reference being had to the accompanying drawing, forming a part thereof.

Figure 1 is a perspective view of an automobile trailer embodying my new design, the same being shown in its closed condition while in transit. Figure 2 is a similar view thereof showing the trailer in its open or in-use condition. Figure 3 is a rear end perspective view of the trailer in its open condition.

The characteristic features of my design reside in the portions shown by full lines in the drawing.

I claim:

The ornamental design for an automobile trailer, substantially as shown and described.

WALTER C. SMITH.
